CONNECTOR FOR SHAKER CONVEYERS

John A. MacPherson and Edward Lasnik,
Erie, Colo.

Application March 28, 1941, Serial No. 385,614

6 Claims. (Cl. 198—220)

This invention relates to the type of conveyer used in coal mines known as a shaker conveyer and consisting of a series of trough-like pans connected together in a continuous line with means for shaking the entire length of pans to cause the coal to travel therealong.

At present, these pans are connected together by means of nuts and bolts. These bolts require considerable time for removal and replacement, require two wrenches, become broken and damaged in use, and they and their nuts become lost in the coal.

The principal object of this invention is to provide a connector for connecting the pans in the conveyer which will eliminate the use of bolts and nuts; which will be positive and powerful in operation so as to rigidly maintain the pans in alignment; which has no loose parts to become lost; which will be rapid in operation so that it can be quickly and easily removed or replaced; and which will provide means for engaging the usual chain hanger by means of which the conveyer is suspended from the mine roof.

Other objects and advantages reside in the detail construction of the invention, which is designed for simplicity, economy, and efficiency. These will become more apparent from the following description.

In the following detailed description of the invention reference is had to the accompanying drawing which forms a part hereof. Like numerals refer to like parts in all views of the drawing and throughout the description.

In the drawing:

Fig. 1 illustrates the improved connector in place on a typical shaker conveyer joint;

Fig. 2 is a cross section through the conveyer, taken on the line 2—2, Fig. 1;

Fig. 3 is a side elevation of the improved connector, partially broken away to illustrate the inner construction;

Fig. 4 is a side view of an alternate form thereof; and

Fig. 5 is a detail perspective view of an attachment which may be used with the alternate form of the improved connector.

In the drawing, the pans of a typical shaker conveyer are indicated at 10 and the suspension chains, by which means the conveyer is suspended from the roof or other support, are illustrated at 11. Such pans are provided at each extremity with a flat cross bar 12 riveted or otherwise secured thereto. These bars 12 extend across the bottom of the pan, as illustrated in Fig. 2, thence are rolled to form sleeve-like loops 13, thence

extend upwardly to support the sides of the pan, to which they are secured by means of suitable rivets 14.

In the usual conveyer, the adjacent cross bars are secured together by means of large bolts extending through the two loops 13 to clamp the extremities of the two pans 10 together. This invention makes use of the loops 13 and the bar 12 without changes therein.

The improved connector consists of a clamp screw 15 provided with right hand threads 16, adjacent one extremity, and left hand threads 17, adjacent its other extremity. Each extremity of the clamp screw terminates in a hexagonal or square wrench receiving head 18. The middle of the bar is preferably left unthreaded.

An L-shaped jaw member 19 is threaded on the threads 16 and a similar jaw member 20 is threaded on the threads 17. The jaw member 19 carries a stud 21 of a diameter which fits snugly in the loops 13 and the jaw member 20 carries a stud 22 of similar diameter. It is preferred to make the stud 22 much longer than the stud 21, as illustrated in Fig. 2.

25 To attach the device to a pan line joint, it is only necessary to swing the jaws 19 and 20 out of alignment with each other, thence insert the longer stud 22 through both loops 13. The jaw 19 is then swung into alignment and the clamp screw is rotated to cause both jaws to approach each other until the short stud 21 enters its loop 13. Further tightening draws the two pans together.

30 It is desired to call attention to the fact that to remove the connector the screw need be rotated only sufficiently to separate the two jaws the length of the short stud 21. The latter can then be swung aside to allow the long stud 22 to be withdrawn.

35 Thus, for the entire removal and replacement of the device, a movement of only one inch or less is necessary and since this movement is divided between two opposite threads, the movement of the screw is divided in half. Thus, but little time and labor is required to remove or replace the connector, whereas with the old style bolts, the nut must be completely unscrewed the entire length of the bolt and completely removed before the bolt can be withdrawn.

40 The long stud 22 acts to accurately maintain the two loops in alignment. However, it has been found that due to the construction of the pans, which are self-aligning, an alignment member through both loops is not always necessary. For such cases the connector may be

manufactured as shown in Fig. 4 with two short studs, as illustrated at 23, and 24, which, of course, facilitates the removal and replacement of the device.

Should it be necessary, when using the latter form of this device, to provide means for aligning the loops, this can be accomplished by means of an attachment such as illustrated in Fig. 5, consisting of a short bar 25 of a diameter to slip within the two loops 13. An ear 26 projects from the mid-portion of the bar 25 and is provided with an opening 27. In use, the fixture of Fig. 5 is placed between the two jaws of Fig. 4 with the opening 27 surrounding the unthreaded mid-portion of the clamp screw 15 as indicated in broken line in Fig. 4.

When using the attachment, it is first placed between the two loops 13 and the latter are forced against the ear 26 thereon. The two jaws are then swung to positions opposite the loops 13 so that the studs 23 and 24 will enter the former. The clamp screw 15 is then tightened to bring the pans tightly together.

A hook-shaped clevis 28 is carried by each of the connectors. Each clevis carries an ear plate 29 having a hole through which the clamp screw 15 passes. The ear is positioned on the unthreaded mid-portion of the screw between the two jaws and is free to rotate thereabout. The looped extremity of each clevis is brought close together in parallel relation to form a narrow slot for receiving a chain link edgewise as illustrated. This prevents the next adjacent link from passing through the clevis and firmly locks the chain in place.

The chain is prevented from falling from the clevis by a hinged latch 30 which is pivoted at 31 on the free end of the clevis to close the loop thereof. When in place on the chains the clevises swing upwardly against the sides of the pans to form side supports therefor.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. A connector for a shaker conveyer of the type having pans terminating in aligned bolt loops comprising: a pair of L-shaped jaws; a threaded passage extending throughout the length of the longer leg of each jaw, the respective passages being oppositely threaded; a clamp screw having oppositely threaded extremities passing through said passages; wrench engaging faces in the extremities of said screw; and a stud extending inward from the shorter leg of each jaw in alignment with each other.

2. A connector for a shaker conveyer of the type having pans terminating in aligned bolt loops comprising: a pair of L-shaped jaws; a

threaded passage extending throughout the length of the longer leg of each jaw, the respective passages being oppositely threaded; a clamp screw having oppositely threaded extremities passing through said passages; wrench engaging faces in the extremities of said screw; a stud extending inward from the shorter leg of each jaw in alignment with each other; and means mounted on said screw for engaging a suspending chain.

3. A connector for a shaker conveyer of the type having pans terminating in aligned bolt loops comprising: a pair of L-shaped jaws; a threaded passage extending throughout the length of the longer leg of each jaw, the respective passages being oppositely threaded; a clamp screw having oppositely threaded extremities passing through said passages; wrench engaging faces in the extremities of said screw; a stud extending inward from the shorter leg of each jaw in alignment with each other; and a hook-shaped clevis mounted on said screw intermediate said jaws for engaging a suspending chain.

4. A connector for a shaker conveyer of the type having pans terminating in aligned bolt loops comprising: a pair of L-shaped jaws; a threaded passage extending throughout the length of the longer leg of each jaw, the respective passages being oppositely threaded; a clamp screw having oppositely threaded extremities passing through said passages; wrench engaging faces in the extremities of said screw; and a stud extending inward from the shorter leg of each jaw in alignment with each other, one of said studs being sufficiently long to overlap the other jaw member, the other of said studs being relatively short.

5. A connector for a shaker conveyer of the type having pans terminating in aligned bolt loops comprising: a pair of L-shaped jaws; a threaded passage extending throughout the length of the longer leg of each jaw, the respective passages being oppositely threaded; a clamp screw having oppositely threaded extremities passing through said passages; wrench engaging faces in the extremities of said screw; a stud extending inward from the shorter leg of each jaw in alignment with each other; an ear member rotatably mounted on said screw intermediate said jaws; and oppositely extending studs on said ear positioned in alignment with the first studs.

6. Means for attaching a shaker conveyer to its suspending chains comprising: hook-shaped clevises having narrowed loop portions for engaging an edgewise-positioned chain link; means for securing said clevis to the standard bolt loops with which the pans of standard shaker conveyers are provided; and a latch member hinged to one extremity of said clevis so as to swing against the other extremity thereof to hold a chain in place therein.
